UNITED STATES PATENT OFFICE

156,357

INVALID'S BATHTUB SEAT

Walter Marti, Saginaw, Mich.

Application September 30, 1948, Serial No. 148,895

Term of patent 14 years

(Cl. D15—8)

To all whom it may concern:

Be it known that I, Walter Marti, a citizen of the United States of America, residing at Saginaw, in the county of Saginaw and State of Michigan, have invented a new, original, and ornamental Design for an Invalid's Bathtub Seat, of which the following is a specification, reference being had to the accompanying drawing, forming part thereof.

In the drawing:

Fig. 1 is a perspective view showing my invalid's bathtub seat.

Fig. 2 is a side-elevational view thereof.

I claim:

The ornamental design for an invalid's bathtub seat, as shown.

WALTER MARTI.
